GRAIN CLEANING AND TREATING APPARATUS

William Walker, Columbus, Kans.

Application October 12, 1955, Serial No. 539,977

9 Claims. (Cl. 209—10)

2

scale showing the manner in which the endless conveyor is disposed between the cleaning cylinder while rotated;

Figure 9 is an enlarged sectional view taken substantially on line 9—9 of Figure 1;

Figure 10 is an enlarged sectional view taken substantially on line 10—10 of Figure 1 with the clamp ring in position; and

Figure 11 is an exploded perspective view of the support and clamp rings for the upwardly opening bags.

Indicated generally at 10 is the novel seed cleaning machine which includes a housing member 12 incorporating end wall members 14 and 16 suitably secured to side wall members 18 and 20. The end wall 14 includes a pair of downwardly opening notch portions 22 and 24 for accommodating therein suitable ground engageable wheels 26 which are secured to the support shaft 28 which is secured exteriorly adjacent the lower end of the end wall 14 by means of suitable journaling bracket elements 30. Thus when the end wall 16 is raised upwardly the seed cleaning machine may be readily transported. The aforementioned vertical lifting is accomplished by means of a handle assembly 32 secured by means of leg portions 34 which are intermediately pivoted by means of a suitable pivot element 36 to the side walls 18 and 20, the legs 34 being secured at their outer ends 38 by means of a suitable handle member 40, the inner ends 42 being engageable on the upper surface of a laterally projecting abutment element 44, and thus when the handle element 40 is lifted upwardly the legs 34 will pivot about the pivot portion 36 urging the ends 42 into engagement with the abutment element 44 and thus the seed cleaning machine may be readily transported. As seen in Figure 2, the handle assembly 32 will be normally disposed with the handle 40 extending downwardly when the machine is not being transported.

For the purpose of description the end wall 14 will be designated as the forward end of the machine whereas the end wall 16 will identify the rear end of the machine.

The housing member includes an upwardly opening upper portion identified generally at 46 and being comprised of suitably secured downwardly angulated side walls 48 and 50, and end walls 52 and 54. The bottom portion of the hopper 46 is defined by an endless conveyor assembly 56 rotatable in a direction to carry uncleared seed toward the hopper wall portion 54 for a purpose to be subsequently described, said conveyor including a pair of transverse shafts 58 and 60 suitably supported by means of depending bracket elements 62 and 64, see Figure 3, which include transversely aligned aperture portions rotatably receiving a drive shaft 66 therethrough, said drive shaft being fixedly secured in the roller element 53, and having suitable sprocket elements 68 secured thereon over which are journaled endless chains (not shown) for driving the conveyor assembly 56 in a well known manner. The conveyor 56 includes an endless belt portion 70 having a plurality of transverse slats 72 extending upwardly therefrom for aiding in moving the uncleared seed toward the wall 54 of the hopper. As most clearly seen in Figure 2, the hopper wall 54 terminates short of the conveyor 70 defining an open space 74 through which the seeds may fall when moved by the conveyor assembly. The space 74 is controlled by means of a feed gate element 76 which is juxtaposed on the hopper wall portions 54 and reciprocates toward and away from the conveyor belt 70 through the expedient of a suitable elongated slot in the gate element 76 and a wing nut assembly 78.

A pair of transversely spaced longitudinally extending rotatable shafts 80 and 82 extend in suitable journal portions between inner surface portions of the end walls 14 and 16, said shafts having secured thereon roller elements 84 which may have a rubber covered periphery 86, the

This invention relates generally to separation apparatus and is more particularly concerned with a novel seed cleaning, treating and dispensing machine.

A principal object of invention is to provide a unitary relatively compact seed cleaning machine incorporating a readily accessible hopper for subjecting uncleared seed at a controlled rate to a rotating apertured cleaning cylinder and air draft for affording material separations in which the separated clean seed is subjected to a pressure dispensed treatment substance before subsequent conveying and disposition in bags.

A further object of invention in conformance with that set forth above is to provide in a seed cleaning machine of the character set forth a power rotated open ended cleaning cylinder having at least two banks of adjustable longitudinally disposed annular aperture portions affording a plurality of material separations through said banks of apertures and out of a rear end portion of said cylinder due to a forced draft and rotation of said cylinder.

Another object of invention in conformance with that set forth above is to provide in a seed cleaning machine of the character set forth means for pressure dispensing a seed treatment substance incorporating novel means for applying said treatment substance to the cleaned grain prior to passage into a mixing drum, said nozzle communicating with a pressure chamber providing a screened treatment substance wherein said pressure chamber communicates between a pressure pump and treatment substance reservoir between which the treatment substance is circulated.

A further object of invention is to provide a readily usable bag support assembly comprising a resilient support ring adjustably and removably supported from a vertical support surface and including a resilient support ring and clamping ring for removably securing a bag in an upwardly opening position.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the novel seed cleaning machine;

Figure 2 is a longitudinal sectional view taken substantially on line 2—2 of Figure 1;

Figure 3 is a transverse sectional view taken substantially on line 3—3 of Figure 2;

Figure 4 is a fragmentary sectional view taken substantially on line 4—4 of Figure 2;

Figure 5 is a sectional view taken substantially on line 5—5 of Figure 3;

Figure 6 is an enlarged sectional view taken substantially on line 6—6 of Figure 3;

Figure 7 is an enlarged vertical sectional view taken through the pressure chamber and distributing nozzle for the treatment substance;

Figure 8 is a sectional view on a somewhat enlarged

shaft 82 being secured thereon in a suitable drive pulley member 88 driven by a drive belt 90 journaled over a drive pulley 92 operatively connected to a suitable power source such as the internal combustion engine indicated generally at 94.

A horizontally disposed open ended grain cleaning cylinder is indicated generally at 96 and includes an outer shell portion 98 being annularly apertured by means of suitable aperture portions 100 which extend longitudinally thereon, the outer shell being engageable on solid peripheral end portions 102 and 104 in running engagement with the rubber surface 86 of the drive wheels 84. The seed cleaning cylinder is thus driven through the expedient of the engine 94 by means of peripheral engagement of drive wheels 84 thereon, and accordingly it rotates about its longitudinal axis and includes no interior obstructions.

Intermediately of the shell 98 is an annular ring element 106 which is in engagement and fixedly secured to the inner periphery of the outer shell, and which is engageable with the ends of a pair of inner shells or drums 108 and 110 each of which including a plurality of longitudinally extending and annularly disposed apertures of a different size than those in the outer shell, and alignable therewith, the inner shells being rotatable about their longitudinal axis relative to the outer shell for providing various degrees of adjustment between inner and outer shells.

The inner cylinders 108 and 110 respectively include penetrating apertures 112 and 114, and the previously mentioned adjustment is accomplished by wing bolt assemblies 116, see Figure 6, extending from the outer shell 98 through a suitable aperture portion 118 in the inner shell 108, said bolt 116 having circumscribed thereon a suitable washer member 120 engageable by a wing nut element 122. The aforementioned adjustment permits the forward portion of the cleaning cylinder to have passed through the cooperating apertures of the cylinders 108 and 98 a relatively smaller sized material, or larger if desired, other than that which is removed through the cooperating apertures of the cylinders 110 and the cooperating aperture portion of the cylinder 98, the material passing therethrough comprising the seeds which will have been cleaned and treated as will be subsequently described.

As previously mentioned, the cleaning cylinder 96 will be rotated and accordingly uncleared seed will be moved rearwardly along the inner peripheral portion of the cylinder where the aforementioned operations of material will take place. Relatively large material such as stones, etc. will be moved rearwardly out of the rear open end 118 of the cleaning cylinder passing over a suitable trough element 123 and onto the ground, or into a suitable container.

It will be noted, see Figure 2, that a suitable transverse plate element 125 is provided beneath the conveyor assembly 56 in the bottom of the hopper 46 for catching uncleared seed to be subsequently moved toward the front end of the hopper. The hopper portion 54 includes a depending trough element 124 secured in any suitable manner and having a free end portion 126 for directing the uncleared seed, see the direction arrows, into the interior of the cleaning cylinder 96.

Mounted on the inner surface of the end wall 14 of the housing member in coaxial alignment with the longitudinal axis of the cleaning cylinder 96 is a force draft propeller assembly 128 comprising a suitable shaft journal bearing portion 130 suitably secured in any convenient manner to the inner surface of the end wall 14, said journal portion 130 rotatably supporting a propeller shaft 132 having secured on the end thereof a suitable propeller 134, said shaft having a drive pulley 136 fixedly secured to an intermediate portion thereof, said drive pulley having journaled thereover a drive belt 138 which is driven by the pulley 88 which drives the clean-

ing cylinder assembly 96. It will be noted that the pulleys 88 and 136 have reduced and increased diameter band portions so that the propeller 134 may be driven more rapidly than the cleaning cylinder for the purpose of providing a suitable force draft therethrough for removing light chaff, straw, etc. which may be intermingled with or commonly found in the seeds being cleaned.

As seen in Figures 1 and 2, the end wall 14 includes a pair of vertically disposed elongated parallel slots 140 and 142 which are disposed on opposite sides of a suitable aperture portion, circular if desired, conforming to the diameter of the propeller 134 and extending through the end wall 14, said aperture portion being indicated at 144. A plurality of vertically adjustable slats 146 extend transversely across the aperture portion 144 and have end tab portions 148 which have extending therethrough suitable wing nut assemblies 150, see Figure 9, which may be loosened permitting the vertical adjustment of the slats 146 for providing more or less of the aperture portion 144 in the end wall 14 to be opened, thus permitting a greater or lesser volume of air to be drawn through said aperture 144. This expedient will thus provide a greater or lesser velocity of air to pass through the open cleaning cylinder 96.

It will thus be apparent that four different separations of material are possible, the first being accomplished by means of the forced draft assembly, the second and third being accomplished by the variation of the aperture sizes between outer shell 98 and the respective inner shells 108 and 110, the last separation being that which passes out of the rear open end of the cleaning cylinder assembly 96.

Disposed beneath the forward portion of the outer shell 98 of the cleaning cylinder 96 are a pair of transverse roller support shafts 152 and 154, see Figure 2, which support thereover a suitably journaled endless conveyor 156 having suitable transverse slats 158, said conveyor receiving the material separated from the aforementioned cooperating inner and outer shell portions of the cleaning cylinder assembly and conveying the same forwardly within the housing member as see by the direction arrow, said separated material comprising principally weed seeds, smaller grain seed, etc. which is desirably separated from the seed to be subsequently treated. Disposed beneath the conveyor 156 in any suitable manner is a transverse plate member 160 for receiving thereon the material dropping past the conveyor 156. A suitable drive shaft 162, see Figure 3, extends through the roller 152 and includes at one end a drive pulley 164 having a drive belt 166 journaled thereover, said belt 166 being journaled over a pulley member 168 mounted on the distal end of the drive shaft 66 for driving the previously mentioned conveyor belt 70 of the conveyor assembly 56 in the hopper. The other end of the shaft 162 has secured thereon a driven bevel gear element 170 engageable with a suitable driving gear 172 mounted on the shaft 80 extending longitudinally in the housing member previously described and driven by virtue of peripheral engagement of the wheels 84 and their rubber surface 86 in contact with the cleaning cylinder 96.

A pair of longitudinally spaced rearwardly disposed transverse shafts 174 and 176, see Figure 2, have journaled thereon an endless conveyor belt 178 extending substantially along the length of the outer shell of the seed cleaning cylinder in which the inner shell 110 is incorporated, and having suitable transverse slat portions 180 for engagement with cleaned seed dropping through the cooperating parts of the cleaning cylinder, said conveyor belt 178 having disposed therebeneath in any suitable manner a transverse plate 182 for catching seed thereon. As seen in Figure 8, the shaft 174 has extending therethrough a shaft 184, and the shaft 162 and 184 each support thereon suitable pulley members 186 and 188 having journaled thereon a suitable twisted drive belt 190 for driving the conveyor belts 156 and 178 in forward

and rearward directions, respectively, see the direction arrows in Figure 2.

Disposed beneath the cleaning cylinder 96 and extending longitudinally between suitable bearing journal portions 192 and 194 suitably secured on oppositely disposed inner surface wall portions of the end walls 14 and 16, respectively, in any suitable manner, said journal portions rotatably support a longitudinally extending support shaft 196 which rotatably supports a mixing drum 198, said drum having an open front end 200 and an open rear end 202 defined by an annular flange portion 204, the drum being supported on the shaft 196 by means of suitable transverse spider members 206 suitably secured on the inner periphery of the drum and the shaft. The shaft 196 has located thereon adjacent the rear end wall 16 a suitable pulley member 207 which has journaled thereover a drive belt 208, see Figures 2 and 4, for example, said belt 208 being journaled over a suitable drive pulley 210 fixed to an intermediate portion of the shaft 82 previously described.

Suitably secured in forward depending relationship is a downwardly tapered trough member 212 which receives the cleaned seed from the cleaning cylinder, said trough having a lower end portion 214 extending within the open end 202 of the mixing drum whereby the cleaned seed, which has been treated with a treating substance will be directed.

As seen in Figures 3 and 5 the housing member includes a longitudinally extending partition 216 which separates the hopper, cleaning cylinder and mixing cylinder from a seed conveyor assembly indicated generally at 218 and a seed treatment material reservoir indicated generally at 220. The conveyor assembly comprises a pair of vertically extending walls 221 and 222 having a suitable bottom member 224 extending therebetween, and have disposed therein between an inner surface portion of the side wall 221 and the partition 216 vertically spaced suitably journaled support shafts 226 and 228 having journaled thereon by means of suitable sprockets 230 and 232, respectively, a suitable endless conveyor chain 234 which includes a plurality of transversely disposed seed pickup slats 236 which terminate adjacent the walls of the conveyor duct 221 and 222. The partition 216 terminates at 238, see Figure 3, for receiving treated seed from a downwardly disposed trough member 240 which is integrally secured to the bottom member 224 of the conveyor duct which has an upper end 242 disposed beneath the open end 200 of the mixing drum. The conveyor duct terminates in an upper hood portion 246 and a downwardly directed spout portion 248 having secured thereon in any suitable manner a flexible sleeve 250 having a pivoted open end portion 252 suitably secured thereon for directing cleaned and treated seed downwardly, the flexible sleeve 250 being swingable between the position shown in Figure 1 for filling seed bags 254 as will subsequently be described.

The treatment substance reservoir 220 comprises a tank 256 which extends substantially the length of the housing member having a downwardly sloping bottom portion 258 terminating in a lower narrow sump portion 260 containing therein a suitable pump assembly 262 such as a centrifugal liquid pump, which has an intake portion 264 in direct communication with the interior of the reservoir tank 256, said pump including a lateral drive shaft 266 having a suitable drive pulley 268 secured thereon and driven by a drive belt 270 journaled thereover, said belt 270 being driven by the support shaft 196 of the treating drum in any suitable manner. The pump 262 has an outlet portion 269 which communicates to a suitable conduit 271 terminating in a pressure can 272 having a suitable transverse screen 274 disposed therein, see Figure 7, said screen being interposed between the conduit 271 and a communicating conduit 276 for straining the treatment material therethrough, said con-

duit 276 communicating with an elongated distributing nozzle 278. The nozzle 278 includes an elongated open slot 280 controlled by an elongated valve control member 282 journaled in an elongated housing 284 of said nozzle, the valve member 282 being controlled by means of a laterally extending suitably sealed handle portion 286 extending out of said housing 284. The nozzle 278 is supported in transverse relation to the lower end 214 of the trough 212 and permits the emission of an elongated spray 288 treatment material upon the seed which has been cleaned, and accordingly, the sprayed seed is mixed in the mixing drum 198.

The pressure can communicates with a second conduit 290 which terminates at 292 interiorly of the reservoir tank 256 and serves to agitate or mix the treatment substance contained therein.

Disposed on the outer portion of the side wall 200, see Figure 1, are pairs of vertically extending channel members 294 and 296 having their web portions extending outwardly, each of said web portions including a plurality of vertically disposed securing apertures comprising elongated vertical slot portions 298 connected to a horizontally disposed slot portion 300 terminating in an outwardly disposed vertical slot portion 302 of a shorter length than the first mentioned vertical slot portion 298.

A bag support ring is indicated generally at 304 and includes a resilient circular portion 306 terminating in a pair of straight leg portions 308 which terminate in downwardly directed right angular portions 310. The central portion 306 includes an integral outwardly and angularly extending clip element 312 extending toward the legs 308 for a purpose to be subsequently described. The ring 304 is supported in the channels 294 and 296 by first inserting the leg portions 310 into the longer vertical slots 298, the inherent resiliency of the central portion 306 urging them outwardly away from each other in the horizontal slot portion 300, the legs being supported in the smaller vertical slot portions 302. As seen in Figure 1 the bag 254 is inserted within the circular portion 306 of the support ring in overlying relationship relative to the clip element 312. A fastening or securing ring comprising a conical collar is indicated at 314 and includes a downwardly and angularly directed securing clip 316, the ring and clip 314 and 316, respectively, being at approximately the same angle as the element 312 on the ring 306 to retain the bag 254 in a relatively fixed and upwardly opening position, see Figure 10, while filling of the same, it being understood that two bags 254 may be supported simultaneously in order that the seed cleaning machine will not have to be shut off, this being accomplished by clasping the flexible portion 250 on the conveyor assembly and one bag is filled and swinging the same to the adjacent empty bag.

While not previously described, it will be noted in Figure 3, that the portion 48 of the hopper has a suitable bracket 318 secured thereto, said bracket 318 having fixedly secured thereto in any suitable manner a longitudinally extending brush assembly 320 having a bristle portion 322 which is engageable with the outer peripheral portion of the seed cleaning cylinder when the same is rotated for removing debris from the material separating apertures of said cylinder.

There accordingly has been disclosed a seed cleaning machine which readily conforms to the objects of invention heretofore set forth.

Various positional directional terms such as "front," "rear," "top," etc. are utilized herein to have only a relative connotation to aid in describing the device and are not intended to require any particular orientation with respect to any external elements.

The foregoing is considered as illustrative only of the principles of the invention. Further, since numerous modifications and changes will readily occur to those

skilled in the art, it is not desired to limit the invention to the exact construction and operation shown and described, and accordingly all suitable modifications and equivalents may be resorted to, falling within the scope of the invention as claimed.

What is claimed as new is as follows:

1. An apparatus for cleaning, treating and bagging seed comprising a housing member, an upwardly opening hopper portion in the top of said housing member, seed conveying and dispensing means at one end of the hopper, a horizontally disposed open ended seed cleaning cylinder supported for rotation on its longitudinal axis between said hopper portion, conveying means on said housing member directing seed from said hopper into one open end of said cylinder, force draft means in said housing urging air longitudinally through the cylinder for removing one separation of material from said seed; power rotating means engageable with said cylinder causing longitudinal movement of the seed through the cylinder along the lower inner periphery thereof for removing a second separation of material out the other open end of said cylinder, said cylinder including annularly disposed longitudinally extending aperture portions extending through said cylinder for accommodating the passage of seed therethrough and constituting another separation of material, a horizontally disposed open ended mixing drum supported for rotation on its longitudinal axis beneath said cleaning cylinder, conveying means extending beneath the cleaning cylinder for conveying separated seed into one end of said mixing drum, pressure operated seed treatment dispensing means overlying the last mentioned conveying means for applying a treatment substance upon the separated seed prior to entry into the one end of said mixing drum, power rotating means engageable with said mixing drum for moving treated seed longitudinally out through the other open end of said drum, and seed elevating and dispensing means extending from the other open end of said drum exteriorly of said housing for bagging separated and treated seed.

2. An apparatus for cleaning, treating and bagging seed as set forth in claim 1 wherein the apertured portions extending through said cylinder are comprised of separated banks of different sized aperture portions extending through said cylinder providing plural separations of material, the last bank of apertures accommodating a predetermined size of seed to be separated.

3. An apparatus for cleaning, treating and bagging seed as set forth in claim 2 including oppositely directed conveyors disposed between said cleaning cylinder and mixing drum for moving the plural separations of material toward opposite ends of said housing member.

4. An apparatus for cleaning, treating and bagging seed as set forth in claim 1 wherein said cleaning cylinder includes an outer cylinder including a plurality of annularly disposed longitudinally extending aperture portions, and a pair of inner coaxially aligned cylinders telescopically received in said outer cylinder, said inner cylinders each including a plurality of annularly disposed longitudinally extending aperture portions alignable with the aperture portions of the outer cylinder for providing different separation of material, the aperture portions of the outer and inner cylinders being alignable providing a predetermined sized aperture for permitting the pas-

5. sage of seed therethrough, and adjusting means extending between the outer and inner cylinders permitting respective relative adjusting rotation about the respective longitudinal axes thereof for controlling the size of the cooperating apertures.

5. An apparatus for cleaning, treating and bagging seed as set forth in claim 1 wherein said hopper portion extends longitudinally on said housing, the seed dispensing and conveying means comprising an endless conveyor in the bottom of said hopper, said hopper including adjustable gate means at the receiving end of said conveyor controlling movement of uncleared seed from said hopper, and trough means extending from said gate means directing uncleared seed into the cleaning cylinder.

15. 6. An apparatus for cleaning, treating and bagging seed as set forth in claim 1 wherein said force draft means comprises a propeller member rotatably supported in axial alignment with the longitudinal axis of said cleaning cylinder, said housing member including adjustable aperture means in alignment with said propeller member for controlling the velocity of air directed through said cleaning cylinder.

20. 7. An apparatus for cleaning, treating and bagging seed as set forth in claim 1 including fixed brush means 25 on said housing extending longitudinally in outer peripheral engagement with said cleaning cylinder for removing material from the aperture portions upon rotation of said cylinder.

30. 8. An apparatus for cleaning, treating and bagging seed as set forth in claim 1 wherein the conveying means 35 extending beneath the cleaning cylinder for conveying separated seed into one end of said mixing cylinder comprises a downwardly directed trough element; said pressure operated seed treatment dispensing means comprising an outlet nozzle element transversely disposed in overlying relationship to said trough element providing a uniform pressure spray of treatment substance upon seed passing therebeneath, a treatment substance reservoir in said housing, pressure pump means including an inlet in communication with the bottom of said reservoir, a pressurized treatment substance receiving chamber interposed between the outlet of said pressure pump and said outlet nozzle element, screening means in said chamber interposed between said pump means and nozzle element, and conduit means extending from said pressure chamber and extending into an upper portion of said reservoir for agitating the treatment substance contained therein.

40. 9. An apparatus for cleaning, treating and bagging seed as set forth in claim 1 wherein said seed elevating and dispensing means comprises a downwardly disposed trough element extending from the other open end of said mixing drum to an elevator duct in said housing, a conveyor vertically supported in said elevator duct, and flexible nozzle dispensing means in communication with said elevator duct for filling bags of treated seed.
